By Knightsbridge acq

United States Patent Office.

HENRY H. CULVER, OF KANSAS CITY, MISSOURI.

Design No. 4,365, dated September 27, 1870.

DESIGN FOR A COOK-STOVE.

The Schedule referred to in these Letters Patent and making part of the same.

I, HENRY H. CULVER, of Kansas City, in the county of Jackson and State of Missouri, have invented and produced a new and original Design for a Cook-Stove, of which the following is a specification.

The nature of my design is fully represented in the annexed photographic illustration, to which reference is made.

Claim.

I claim as my invention—

The design for a cook-stove, as shown. In testimony of which invention, I hereunto set my hand.

HENRY H. CULVER.

Witnesses:

GEO. H. KNIGHT,
JAMES H. LAYMAN.
